UNITED STATES PATENT OFFICE.

MILTON B. CRESSWELL, OF DES MOINES, IOWA.

DEFECATOR.

1,134,997.

Specification of Letters Patent. Patented Apr. 13, 1915.

Application filed April 4, 1914. Serial No. 830,064.

To all whom it may concern:

Be it known that I, MILTON B. CRESSWELL, citizen of the United States of America, and resident of Des Moines, Polk county, Iowa, have invented a new and useful Defecator, of which the following is a specification.

The object of this invention is to provide an improved construction for defecators for refining syrups.

10 A further object of this invention is to provide improved means for removing the scum from sorghum juice during the operation of boiling.

15 A further object of this invention is to provide improved means for initiating the process of clarifying juice in a single treatment without the use of lime or other foreign substances.

20 A further object of this invention is to provide improved means for removing the impurities from sorghum juice in a tank by boiling in one end and skimming in the opposite end of said tank.

25 My invention consists in the construction, arrangement and combination of elements hereinafter set forth, pointed out in my claims and illustrated by the accompanying drawing, in which—

30 Figure 1 is a plan of my improved device. Fig. 2 is a vertical longitudinal section of the same. Fig. 3 is a detail vertical section, on an enlarged scale, of one end portion of the tank. Fig. 4 is an elevation of a paddle or scraper employed in removing scum.

35 This invention relates to and is an improvement on devices illustrated, described and claimed in Letters Patent of the United States Number 1,075,629 granted to me October 14, 1913, to which patent reference hereby is made.

40 In the construction of the apparatus as shown the numeral 10 designates generally an open tank or pan, which may be of any 45 desired dimensions, and supported in any suitable manner. A steam pipe 11, fitted with a cut-off valve 12, leads from a source of steam supply (not shown) and enters the tank 10 at one end, over the top thereof.

50 The steam pipe 11 communicates with a steam coil 13 which lies near the bottom of the tank 10 and extends entirely across said tank and approximately one-half the length thereof. One or more of the coils of the 55 pipe 13 at its initial end preferably extend upwardly adjacent the forward end wall of

the tank 10, and are designated by the numeral 14. The steam coil 13 communicates at its inner end with a pipe 15 which leads back across the top of said coil, leads up over the top of the tank, is fitted with a cut-off valve 17, and leads thence to a suitable place of exhaust. The tank 10 is provided, at its end opposite to the steam coils 13, 14, with a plurality of transverse partitions 18, 19, 20, in this instance three in number, which divide that end portion of the tank into a plurality of narrow transverse chambers. The partitions 18 to 20 inclusive are relatively low, being preferably about one-third 60 the height of the walls of the tank. An inclined baffle plate 22 is fixed transversely of the tank 10 beyond the last partition 20, thus forming a scum compartment 23 at the extreme end of said tank. The baffle plate 22 65 preferably is of greater height than the partitions 18 to 20 inclusive but of less height than the walls of the tank, preferably about two-thirds the height of said walls. Discharge pipes 24, 25, 26 lead from the 70 bottom of the tank 10 beyond the respective partitions 18, 19, 20, and a discharge pipe 27 leads from the bottom of the scum chamber 23. The discharge pipes 24, 25, 26, 27 75 lead into a common pipe 28, controlled by a valve 29 between the pipes 26, 27, which pipe leads to a suitable place of discharge, such as a sewer. The passage of the pipes 24, 25, 26, 27 through the bottom of the tank 10 is made water-tight, preferably by the 80 use of lock nuts on opposite sides of said bottom. A pipe 30 leads from the forward portion of the bottom of the tank 10 to a suitable place of discharge of semi-syrup, such as a finishing evaporator (not shown). 85 The pipe 30 is controlled by a cut-off valve 31.

90 In the practical use of the apparatus juice to be defecated is introduced to the tank 10 in any desired manner, as by pouring or piping. Steam is admitted to the pipe 11 95 by opening the valve 12, and passes thence to the coils 13, 14 and pipe 15. The heating of the coils 13, 14 by the live steam starts a current in the juice in the tank toward the rear thereof, and the arrangement of said coils results in a current rearwardly at the top of the body of juice. As the juice passes toward the rear portion of the tank and over the partitions 18 to 20 inclusive, the heavier particles of impurities carried thereby will sink and be received be- 100 105 110

tween said partitions, and there held. The juice then encounters the baffle plate 22 and the scum thereon may be removed by a paddle in the hands of an operator, who scrapes 5 it over said baffle plate into the scum chamber 23. A convenient form of paddle for this purpose is shown in Fig. 4, the handle 32 being fixed at an angle to the blade 33, so that in operation the blade may be readily 10 held in horizontal position and swung gently across the top of the juice. When it encounters the baffle plate 22, the current of juice is directed downwardly and returns on a lower plane toward the coils 13, 14, 15 where it again rises and starts in the opposite direction. This operation is continued until the juice has lost the greater part of its impurities and is in the condition known as semi-syrup. The semi-syrup is then 20 drawn off through the pipe 30 for further treatment in other devices (not shown) such as a finisher, where the refining is completed. The low partitions 18 to 20 inclusive provide quiet places for the collection 25 of heavy impurities and sediment, and the juice containing such impurities, and remaining in and behind said partitions, together with the scum in the chamber 23, may be drawn off through the pipes 24, 25, 26, 27 30 and 28, after the defecating operation is completed. Such sediment as remains behind the partitions 18 to 20 inclusive may then be removed by means of shovels or scraped to the drain pipes and removed by 35 flushing. Scum from the chamber 23 is free to flow off at all times through the pipes 27, 28.

The use of this improved apparatus obviates the use of clay or infusorial earth, 40 lime or hand skimming in the removal of impurities from raw syrup, and removes said impurities, to an extent impossible to attain by means of the processes and devices commonly in use. The principle may be 45 stated briefly as boiling in one end of a tank and skimming in the opposite end thereof.

An inclined hood or leaf 34 preferably is fixed to the end wall of the tank 10 over the coil 14 and projects within said tank. It is

the function of the hood or leaf 34 to prevent the syrup in the tank from boiling over the top at that end where the boiling is most severe on account of the vertical arrangement of the coil 14.

I claim as my invention—

1. A defecator, comprising a tank, a steam coil in one end portion thereof, a plurality of relatively low partitions crossing said tank in the end opposite to said steam coil, and an inclined baffle plate crossing said tank beyond said partitions.

2. A defecator, comprising a tank, a steam coil in one end portion thereof, a plurality of relatively low partitions crossing said tank in the end opposite to said steam coil, and an inclined baffle plate crossing said tank beyond said partitions, said baffle plate being of greater height than said partitions and of less height than the walls of the tank.

3. A defecator, comprising a tank, a steam pipe entering said tank, a steam coil arranged in vertical position adjacent the forward end of said tank and communicating with said pipe, a steam coil arranged in horizontal position in said tank and extending approximately to the middle thereof, said latter steam coil communicating with the first steam coil, an inclined hood over the vertical steam coil, and skimming means in the opposite end portion of the tank from said coils.

4. A defecator, comprising a tank, steam coils in one end portion thereof, a plurality of partitions crossing the opposite end portion of said tank, said partitions rising to approximately one-third the height of the tank walls, an inclined baffle plate crossing the tank beyond said partitions and rising to approximately two-thirds the height of the tank walls, and drain pipes beyond said partitions and baffle plate.

Signed by me at Des Moines, Iowa, this twentieth day of December, 1913.

MILTON B. CRESSWELL.
